UNITED STATES PATENT OFFICE.

JOHN JOHNSON, OF BROOKLYN, NEW YORK.

MIXER.

1,354,489.

Specification of Letters Patent.

Patented Oct. 5, 1920.

Application filed June 7, 1916, Serial No. 102,110. Renewed February 21, 1919. Serial No. 278,509.

To all whom it may concern:

Be it known that I, JOHN JOHNSON, a citizen of the United States, residing at Brooklyn, New York, have invented certain new and useful Improvements in Mixers, of which the following is a clear, full, and exact description.

This invention relates to mixers, and particularly to rotary mixers for use in mixing 10 solids, liquids or gases with liquids.

Rotary mixers as hitherto constructed have usually tended in operation to impart to the contents of the mixing tank a whirling motion about the axis of rotation, this 15 whirling motion, with its resultant eddying effect, tending to interfere with those movements of the liquid across the axis of rotation and lengthwise thereof which are necessary for the complete intermingling of the 20 materials to be mixed. Moreover, in the operation of rotary mixers or mixing wheels of the tangential type, the centrifugal flow of the liquid through the wheel tends also to create an eddy in the stream entering the 25 central part of the wheel, and this eddying movement of course reduces the stream to the wheel and consequently the mixing action of the wheel.

An object of the invention is to provide 30 simple and efficient mixing means which will obviate the difficulties heretofore experienced in mixing operations, and will insure an effective intermixing of the contents of the mixing tank.

More particularly the invention aims to provide improved mixing means of the rotary type which will operate to insure movement of the liquid across the axis of rotation, as well as lengthwise thereof, and at 40 the same time will check any tendency to bodily whirling of the tank contents about the axis of rotation.

An important feature of the invention is the arrangement in the stream to the centrifugal wheel, of means for imposing upon the stream a centripetal tendency.

Another important feature of the invention is the provision of means about the periphery of the rotary mixing or tangential 50 wheel for converting the tangential movement of the discharged material into substantially a radial movement.

The invention also contemplates the provision in rotary mixing means of the centrifugal type, of means for causing some or 55 all of the material entering upon one side of

the wheel to be discharged with a tendency to flow to the other side, whereby the wheel may have an intermediate location in the tank and insure an intermingling of the materials upon its opposite sides.

Other objects and important features of the invention will appear from the following description and claims when considered in connection with the accompanying drawings, in which—

Figure 1 is a vertical elevation of the mixing device, the tank in which the device is located being shown in section;

Fig. 2 is a plan view of the mixing mechanism proper;

Fig. 3 is a view of a modified mixing wheel arranged to be located between the top and the bottom of the mixing tank;

Fig. 4 is a plan view of the mixing wheel 75 shown in Fig. 3;

Fig. 5 is a vertical section through the mixing means shown in Figs. 1 and 2;

Fig. 6 is a vertical section through the mixing wheel shown in Figs. 3 and 4; and 80

Fig. 7 is a modification of the type of mixing wheel shown in Figs. 3, 4 and 6.

In the form of the invention shown in Figs. 1, 2 and 5 of the drawings, which is intended for use in the bottom of a mixing 85 tank, the material to be operated upon by the mixing wheel preferably enters the top of the wheel 2 through the opening 4, and is directed toward the periphery of the wheel by turbine blades 6 which create a centrifugal flow of the liquid. From an inspection of Fig. 2 of the drawings it will be noted that these blades are inclined away from the direction of rotation of the wheel 2.

The centrifugal flow of the materials to 95 be mixed created by the action of the blades 6 tends to draw the stream of materials entering the opening 4 toward the inside of the cylindrical wall 8 surrounding this opening, and this action, together with the turning 100 action of the wheel, tends to create a whirling motion of the liquid above the wheel and thus tends to create an eddy in the stream entering the opening 4. To counteract this tendency, I provide blades 10 which are inclined toward the direction of turning of the wheel, as shown in Fig. 5, this inclination increasing from the hub 12 of the wheel toward the periphery, whereby these blades tend to direct the stream entering the opening 4 toward the center of rotation; in other words, they create a centripetal tendency in 105 110

the stream which serves to counteract the centrifugal tendency caused by the action of the blades 6.

In the illustrated construction, the wheel 2 comprises a horizontal plate 14 upon the underside of which the blades 6 are carried, these blades being preferably cast integral with the plate 14, and the cylindrical wall 8 surrounding the opening 4 is preferably 5 carried upon the plate 14, the blades 10 being also preferably for the most part above this plate and extending between the hub 12 of the wheel and the cylindrical wall 8. These parts may all be cast in one integral piece.

As the mixed materials are discharged from the periphery of the wheel 2, they tend to travel in tangential paths and horizontally across the bottom of the tank 16, 10 and then to flow up the sides of the tank to a position above the wheel to replace the material drawn into the center of the wheel. The tendency of the wheel is gradually to 15 set up a whirling motion of the entire contents of the tank in the same direction as the rotation of the wheel. This whirling motion with its accompanying eddying effect tends to counteract the mixing action of the wheel and to throw the tank contents, by centrifugal action, to the outer 20 wall of the tank out of the range of operation of the wheel. To counteract this tendency and insure a positive mixing of the materials and a proper direction of the mixing currents, baffle plates 18 are provided 25 which are preferably so located about the periphery of the wheel 2 and at such angles to the periphery that they intersect the tangentially discharged material and tend to 30 direct it along radial lines, as shown in Fig. 2 of the drawings. These baffle plates may conveniently be formed upon segmental plates 20 which can be attached by screws 22 to the bottom of the tank, six of 35 these baffle-carrying segment plates being 40 shown in Fig. 2 of the drawing.

In the modification of the invention shown in Fig. 3 of the drawings, the mixing wheel is constructed for use at a point 45 between the top and the bottom of the tank, and is designed to insure a mixing of the materials above the wheel with the materials below the wheel. In this construction, the wheel has material-receiving 50 openings 24 and 26 at both its upper and its lower sides, and the blades 28 which produce the centrifugal flow of the materials are carried by a central disk 30, integral 55 with the hub 32 of the wheel. These blades, like the blades of the wheel shown in Figs. 1, 2 and 5, are inclined away from the direction 60 of rotation so as to insure the centrifugal flow of the materials to be mixed, and the materials are confined and guided as 65 they flow toward the periphery of the wheel

by upper and lower plates 34 and 36, which are inclined toward each other as they approach the periphery. From an inspection of Fig. 3 of the drawings, it will be seen that the materials are drawn into the openings 24 and 26 from above and below the wheel respectively, by the centrifugal flow created by the blades 28. In order to insure the proper mixing of the materials without a bodily whirling motion of the tank contents, baffle plates 38 and 40 are 70 preferably provided about the periphery of the wheel, these plates being inclined to the periphery in the same manner as the plates 18 shown in Fig. 2, and in order that part 80 of the stream of discharged material may be directed toward the bottom of the tank and part toward the top, these baffle plates 38 and 40 are formed respectively upon the upper and lower sides of a separating plate 85 42 which surrounds the mixing wheel at its middle.

It will be noted that the streams which enter the upper and lower openings 24 and 26 are discharged from common discharge 90 openings. In other words, the two streams mingle in the wheel, and in order that a part of these mingled streams may be discharged toward the top of the tank and another part toward the bottom, the plates 34 and 36 are preferably so formed that successive discharge openings direct the greater part of the flow in opposite directions. As shown in Figs. 4 and 6 of the drawings, the discharge opening between 100 two successive blades 28 is enlarged by having the upper plate cut back, as shown at 44 in Fig. 6; while the discharge opening between the succeeding blades 28 is enlarged by having the lower plate cut back, as shown at 46 in Fig. 4. Thus the material discharged between two of the blades 28, which consists of a mixture of the material entering the upper and lower openings 24 and 26, will be discharged with a 110 tendency to flow above the separating plate 42, while the material discharged between the succeeding blades 28, likewise consisting of a mixture of the materials entering the openings 24 and 26, will be discharged with a tendency to flow below the plate 42.

In the modification shown in Fig. 7, this separating and distributing action is obtained by making the separating plate 120 which connects the baffles 38 and 40 in the form of alternately upwardly and downwardly directed sections 48 and 50, as shown in Fig. 7. In this construction, the upper and lower plates 34 and 36 of the mixing wheel will extend equally to the periphery 125 about the whole circumference of the wheel.

Any suitable mechanism may be provided for driving the mixing wheel. The mechanism shown in Fig. 1 comprises a vertical shaft 52 upon the lower end of which the 130

wheel is carried, this shaft being supported in a bearing 54, in a bracket 56 carried upon cross pieces 58 extending across the top of the tank, and having upon its upper 5 end a bevel gear 60 with which meshes a bevel pinion 62 upon a cross shaft 64 provided with loose and fast pulleys 66 and 68.

As shown in Fig. 3 of the drawings, the baffles 38 and 40 and the separating plate 10 42 may be attached to the side walls of the tank by brackets comprising a base piece 70 and brace arms 72, 74.

In the present application I have not claimed the invention in its broadest aspects 15 but broad claims to the invention have been incorporated in and allowed in my companion application Serial Number 278,467, filed February 21, 1919.

What I claim as new is:—

20 1. A rotary mixer comprising a rotary body having central receiving openings upon its opposite sides, means for establishing a centrifugal flow through said body of material entering said openings, and 25 means for causing material which has entered the central opening upon each side to be discharged with a tendency to flow to the opposite side of said body.

2. In combination with a liquid container, 30 a tangential mixing wheel, stationary baffles about the periphery of said wheel, and means for directing upward a part of the material discharged by said wheel and for directing downward another part.

35 3. In combination with a vessel, a tangential mixing wheel, stationary baffles about the periphery of said wheel, and means carried by said wheel for directing upward a part of the material discharged by said 40 wheel and for directing downward another part of said material.

4. A rotary mixer comprising a body rotatable about a vertical axis, said body having a central opening extending therethrough, means for establishing a centrifugal flow of material entering said central opening and for confining and guiding said material to the periphery of said body, and

means for directing upward a part of the material discharged from the said periphery and for directing downward another part of the said material. 50

5. A rotary mixer comprising a body rotatable about a vertical axis, said body having a central opening extending therethrough, means for establishing a centrifugal flow through said body of material entering said opening and for confining and guiding said material to the periphery of said body, and means carried by said body 60 for directing upward a part of the material discharged at said periphery and for directing downward another part of said material. 55

6. A rotary mixer comprising a rotary 65 body having central receiving openings upon its opposite sides, means for establishing a centrifugal flow through said body of material entering said openings, means for causing material which has entered the central opening upon each side to be discharged with a tendency to flow to the opposite side of said body, and means for checking the tangential movement of said discharged material. 70

7. A rotary mixer comprising a rotatable body, said body having a central opening extending therethrough, means for establishing a centrifugal flow through said body of material entering said opening, means 80 where the peripheral tangential discharge of said material takes place for directing in one direction along the axis of rotation a part of the material discharged and for directing in the other direction along said axis 85 another part of the discharged material, said directing means being alternately arranged about the axis of said rotary body to insure intermixing of material from the two sides of said body. 90

Signed at New York city, this 6th day of May 1916.

JOHN JOHNSON.
